SIX-WHEEL TRUCK

Filed Feb. 27, 1928

UNITED STATES PATENT OFFICE.

CLARENCE B. HARBISON, OF LIMA, OHIO, ASSIGNOR TO OHIO STEEL FOUNDRY COMPANY, OF LIMA, OHIO, A CORPORATION OF OHIO.

SIX-WHEEL TRUCK.

Application filed February 27, 1928. Serial No. 257,161.

This invention relates to improvements in equalized railway trucks, and has for its principal object to provide a new and improved construction of the character described, wherein the equalizers are readily accessible for inspection and replacement. Other objects of my invention will appear from time to time as the description proceeds.

10 The invention may best be understood by reference to the accompanying drawing, in which

Figure 1 is a side view of a six-wheel truck constructed in accordance with my invention, 15 with parts broken away to show the interior construction thereof,

Figure 2 is a fragmentary plan view showing one end of the truck, with parts of the frame broken away.

20 Referring to details of the drawing, the same illustrate my invention as applied to a six-wheel, or three axle truck, comprising side frames 10, each having three pedestals 11, 11, 11, and cross connected as usual by 25 a pair of transoms 12, and end frame members 13. The wheel axles, and their journal boxes are not shown in detail, as they form no part of the invention.

Each side frame 10 is formed with inner 30 and outer upright walls 15 and 16 respectively, between which are mounted leaf springs 17, 17, above each of the pedestals 11, 11, in position to have supporting engagement on the several journal boxes in the usual manner. The lower wall 20 of the side frame 10 between adjacent pedestals is arched or recessed upwardly as shown, and at the central point of each recessed portion is a fulcrum bearing 22 beneath which equalizer bars 18, 40 are engaged. The central portions of said equalizers are thus disposed in readily accessible position below the side frame, while the ends curve upwardly through apertures 23, 23, into the side frame, where they are 45 connected by pins 21, 21, to vertically disposed spring hangers 24, 24, which engage over adjacent ends of springs 17, 17. A vertical cross web 25 is provided between the side walls 15, 16 above each fulcrum bearing 22,

thus affording desired strength at this point. 50 Access to the springs 17 and hangers 24 may be provided through apertures 26, 27, suitably disposed in the side walls 15, 16, respectively.

A construction as above described affords 55 the advantage of ready accessibility of the equalizer bar for inspection or removal. The pivot pins 21 at opposite ends of the equalizers are slightly higher than the fulcrum of their respective equalizer, thereby affording 60 a more stable arrangement than in prior constructions, where the equalizer bar is fulcrumed within and near the top of the hollow side frame. Said equalizer is removable by simply withdrawing hanger pins 21, 65 21, at opposite ends, and then with dropping one end through the aperture 23, whereupon the opposite end may then be similarly withdrawn.

Although I have illustrated and described 70 one particular embodiment of my invention, it will be understood that I do not wish to be limited to the exact construction shown and described, that that various changes and modifications may be made without departing 75 from the spirit and scope of my invention.

I claim as my invention:

1. In a truck, a side frame having laterally spaced side walls, and longitudinally spaced pedestals with upwardly extending recesses therebetween, equalizing means extending above said pedestals between said side walls, and intermediate connecting equalizers fulcrumed in said recesses beneath said frame.

2. In a truck, a side frame having laterally spaced side walls, and longitudinally spaced pedestals with upwardly extending recesses therebetween, equalizing means extending above said pedestals between said side walls, and intermediate connecting equalizers fulcrumed in said recesses beneath said frame, and vertically disposed reinforcing webs connecting said side walls above the fulcrum points of said equalizers.

Signed at Chicago, Ill., this 24th day of February, 1928.

CLARENCE B. HARBISON.
